UNITED STATES PATENT OFFICE.

CARL E. CHRISTOPHEL, OF PEARL RIVER, NEW YORK, ASSIGNOR TO DEXTER FOLDER COMPANY, OF PEARL RIVER, NEW YORK, A CORPORATION OF NEW YORK.

SHEET-FEEDING MACHINE.

1,320,203.

Specification of Letters Patent.

Patented Oct. 28, 1919.

Application filed March 12, 1918. Serial No. 221,939.

To all whom it may concern:

Be it known that I, CARL E. CHRISTOPHEL, a subject of the German Emperor, residing at Pearl River, in the county of Rockland and State of New York, have invented certain new and useful Improvements in Sheet-Feeding Machines, of which the following is a specification.

This invention relates to sheet-feeding machines and has for its primary object to provide improved means for registering sheets as they are fed from a pile to some other machine, such as a printing press, folding machine, etc. One of the objects of my invention is to provide improved sheet-registering means according to which that edge of the sheet which strikes against the gage, is stiffened by being warped or crimped along lines extending transversely to the gage or plate which registers its positions. Specific objects of invention reside in the peculiar means provided for warping or crimping the front edge of a sheet as well as either lateral edge of said sheet. Another object is to provide improved "trip-off" means for interrupting the operation of the machine whenever a sheet fails to register properly. Ancillary objects of invention are found in the means for releasing or discontinuing the operation of the sheet-crimping means on either or both sides of the machine. Other and further objects will appear in the specification and be pointed out in the appended claims, reference being had to the accompanying drawings which exemplify my invention in a preferred embodiment.

In the drawings,—

Figure 1 is a top plan view of a sheet-feeding machine constructed in accordance with the principles of the present invention, parts being broken away;

Fig. 2 is a top plan view of one end of the same on an enlarged scale, parts being broken away;

Fig. 3 is a side elevation of the parts shown in Fig. 2, parts being broken away;

Fig. 4 is a side elevation similar to that shown in Fig. 3, with the parts in changed positions;

Fig. 5 is a similar side elevation showing the relative positions of the parts during the transmission of power from the cam shaft to the side-registering gage operating rock-shaft;

Fig. 6 is a section on the line VI—VI, Fig. 2, parts being broken away;

Fig. 7 is a side elevation of the front sheet-buckling means, some of the contiguous parts being removed for the sake of clearness and other parts shown in section; Figs. 8 and 9 are diagrammatic transverse sections of the buckling members in inoperative and operative positions respectively;

Fig. 10 is a front elevation of the side-gage buckling means, parts being broken away and parts shown in section;

Fig. 11 is a similar front elevation, the parts being shown in changed positions;

Fig. 12 is a section on the line XII—XII, Fig. 10, parts being broken away and parts omitted;

Fig. 13 is a side elevation of the side-registering gage supporting bracket;

Fig. 14 is a section on the line XIV—XIV, Fig. 12;

Fig. 15 is a fragmentary section showing details of the side-registering gage adjusting means, parts being shown in elevation;

Fig. 16 is a top plan view of the gripper, the reciprocating rack connected thereto being shown in section and broken away at one end.

In the embodiment of my invention shown in the drawings, the sheet-feeding means includes feed tapes 1 passing at their forward ends about roller 2 which extends transversely of the machine. As shown best in Figs. 3, 4 and 5, a rod 3 which may be reciprocated by any suitable means (not shown on the drawings), is pivotally connected at 4 to a cam 5 on a cam shaft 6. The cam 5 has concentrically spaced peripheral portions 5^a and 5^b with an interposed notch 7 or recess 7. Extending radially from the shaft 6 and centrally disposed with respect to notch 7 is a rib or tooth 8 which is adapted to engage in a notch 9 formed in a plate or segment 10 which is keyed to a rock shaft 11. The plate or segment 10 comprises two angularly arranged wings 12 with circular faces 13 which are adapted to slidably fit the circumferential portions 5^a and 5^b and to alternately lock the rock shaft 11 against movement for periods after each oscillation by the tooth 8. The connection between the cam shaft 6 and rock shaft 11 constitutes a form of Geneva gear. Referring to Fig. 13, an irregularly shaped bracket is shown

which comprises a body portion 14 with upwardly projecting bearing lugs 15 and 16 which slidably engage the rock shaft 6 so as to be adjustable longitudinally of said shaft. For this purpose, the bearing lug 16 is provided with a laterally projecting sleeve 17 which is threaded exteriorly for the reception of thumb nuts 18 and 19. Interposed between the thumb nuts 18 and 19 is the boss 20 carried by an arm or lever 21 which projects upwardly from a boss 22 which is keyed to a rod 23 which extends transversely across the machine. The boss 20 thus constitutes a fixed abutment relatively to which the bracket 14 may be adjusted by manipulating the thumb nuts 18 and 19. The body portion 14 of the bracket is grooved to form oppositely disposed guiding surfaces 24¹ and back of said guiding surfaces a recess with guiding surfaces 24 for accommodating the bifurcated hub of a movable gripping jaw to be hereinafter referred to. Extending laterally from the body portion of the bracket is a plate or flange 25 (see Fig. 13) which as shown in Fig. 14, is provided with spaced downwardly projecting bearing flanges 26 which straddle the rod 23, thereby serving to guide the bracket whenever it is adjusted. Between the guiding surfaces 24¹ is mounted a slide comprising a solid block portion 27, a lower flange or plate 28 and an upper flange or plate 29 beveled below at its outer end and provided in its top surface with a skew rack 30. The rack 30 meshes with a segmental skew gear 31 provided with a hub 32 which is keyed to the rock shaft 11. It will thus be understood that whenever the shaft 11 is rocked on its axis the slide 27 will be reciprocated transversely of the direction of feed imparted to a sheet by the tapes 1. The slide 27 carries a pin 33, the oppositely projecting ends thereof serving to pivot the deflected bearing portions 34 of a movable gripper jaw 35. The lower flange or plate 28 constitutes a fixed gripper jaw relatively to which said jaw 35 opens and closes. Projecting from one of the bearing portions 34 is an arm 36 which is shown best in Figs. 10 and 11, which carries a pin 37, upon which pivots a trip lever or dog comprising a cam arm 38 provided with a roller 39 and a lever arm 40. The lever arm 40 is adapted to abut against a shoulder 41 provided on the arm 36 of the movable jaw and to force said jaw into open position in the manner to be hereinafter pointed out. Coöoperating with the cam roller 39 at certain times during the operation of the machine, is a cam bar 42 provided with spaced integral plates 43 which project upwardly therefrom and by means of which said cam bar is secured to the adjustable bracket by means of screws 44. Secured to the bracket 14 is a plate or bar 45 which carries at its rear end a boss

46 in which is threaded a screw abutment 47 which is adapted to engage the arm 40 of the trip dog to force it into the position shown in Fig. 11 whenever the slide 27 is moved to its right hand extreme position. 70 Projecting rearwardly from the left hand end of the movable jaw 35, is a pin 48 which serves to journal a roller 49 (shown in dotted lines in Fig. 12). As the jaw is raised and lowered, the roller 49 serves to operate a 75 crimping device which will now be described. Extending rearwardly from the bracket 14 is an arm 50 carrying a laterally projecting pin 51 on which is pivotally mounted a crimper by means of spaced bearing lugs 52. Said crimper comprises an upper flange 53 (see Fig. 14) which is engaged by the roller 49 and a lower flange 54 which is adapted when lowered into the position shown in dotted lines in Fig. 14, to crimp 80 or warp a sheet along its edge which is being moved to a gage and thus to stiffen it to resist the impact due to its momentum. The thumb screw 55 which is threaded in the crimper is adapted to adjustably engage a 85 flange or lug 56 which projects laterally from the arm 50 of the bracket, thus adapting the crimper to be held in raised position on either side of the machine. A sheet gage 57 is secured by screws 58 to the bracket 14 and partakes of the adjustments of said bracket. As shown in Fig. 11, the lower flange 54 of the crimper is deflected downwardly at 54^a adjacent the side gage 57. It will also be noted in Fig. 12, that said lower flange inclines forwardly as shown by the dotted line 54¹ so that the crimping effect is widened and deepened as the edge of the sheet approaches the side gage. Means are provided for imparting a normal tendency 90 to press the movable jaw down onto the fixed jaw of the gripper by a spring 59 which is secured at one end to a pin 60 rigid with the bracket 14 and at its other end is engaged by a pin 61 carried by a knurled 95 nut 62 provided with notches 63 by means of which said nut may be engaged by radial pins 64 carried by the pin 33 which moves with the movable jaw. The tension on said movable jaw may thus be adjusted to meet 100 requirements.

Referring now to Figs. 3 to 6, the cam 5 is provided with an annular slot 66 within which is adjustably mounted a bolt 67 which is threaded to receive a clamping nut 120 68 on one side of the cam 5, while on the outer face of the cam it carries a lug or abutment 69 which is adapted at certain times to engage a lug or shoulder 70 on a bar 71. Said bar 71 is pivotally mounted 125 at 72 on the upper arm of a lever 73 which is pivoted on a stud 74, the lower arm of said lever being pivotally connected at 75 with the forward end of the rod 76 which is adapted to operate a trip-off mecha- 130

- nism (not shown on the drawings). The forward end of the bar 71 rests upon a pin 77 which projects laterally from a lever arm 78 which is keyed to a transverse shaft 79.
- 5 Depending from the shaft 79 is a lever arm 80 from which is pivotally suspended at 81, on either side of the machine, a detector finger 82 which is adapted to engage in the hole or depression 83 in the front plate 84 whenever a sheet does not cover such opening or depression. Projecting upwardly and rearwardly from the shaft 79 is a cam arm 85 which carries a roller 86 which normally engages the cam 5 when the holes or 10 depressions 83 are covered by a sheet. Whenever such holes are not covered by a sheet, the detector fingers 82 catch thereon as shown in Fig. 5, so that the cam roller 86 is prevented from following into the inner 15 run 87 of the cam 5. The cam 5 is also provided with an intermediate run 88 into which a cam roller 89 is adapted to follow at certain times. Said cam roller 89 is carried by a cam arm 90 which is keyed to a 20 rock shaft 91 which also carries a lever arm 92 in the outer end of which is mounted an adjustable abutment 93 which is adapted to rest on the cam shaft 6. A spring 94 is connected at opposite ends to the cam arms 85 25 and 90 and thus serves to draw these arms toward the cam 5. Rock shaft 91 is adapted to operate a combined slow-down and crimping device which will now be described. On either side of the machine or on both 30 sides thereof, the rock shaft 91 according to the present embodiment of my invention, carries a bifurcated crimping device 95 with forwardly projecting fingers 96 which are adapted to be raised and lowered by the 35 oscillations of the rock shaft 91. Coöperating therewith is an upper crimping device or finger 97, said upper finger being carried by a bracket 98 which is secured by a set screw 99 on the stationary cam shaft 6.
- 40 In Figs. 3 and 4, is shown a front sheet gage 100. The operation of the feeding mechanism will now be readily understood and briefly described is as follows:
- 45 As a sheet is fed forwardly by the tapes 1, the rock shaft 11 is oscillated by the Geneva connection with cam 5 to move the reciprocating gripper inwardly. At the end of its last outward movement, the dog 38 has been moved into vertical position shown 50 in Figs. 10 and 11, thus raising the movable gripper jaw 35 so that the sheet in its forward movement passes between said jaws. These movements are brought about by the cam 5 moving in the direction of the arrow 55 shown in Fig. 3, the process of rocking shaft 11 being shown in Fig. 5, after which the open jaws remain in their innermost position for a brief period of time. At the 60 same time, the movement of said cam 5 has permitted the rock shaft 91 to move the 65 lower crimping elements of the front crimpers into the position shown in Fig. 7, the relative positions of the crimping elements being shown in Fig. 9. As the sheet moves forward the retardation is gradually increased until it slows down and comes into engagement with the front gage 100. At the same time, the sheet becomes warped in such a way as to form reinforcing flutings which strengthen it to resist the impact on gage 70 75 100. As the cam 5 begins its return movement in the direction of the arrow shown in Fig. 4, the front edge crimpers release the sheet, after which a return oscillation is imparted to the rock shaft 11 which in turn 80 moves the slide 27 outwardly. At the commencement of this movement, the dog 38 is displaced by its engagement with the cam bar 42 and thus releases the movable gripper 85 90 95 100 105 110 115 120 125 130 35 which falls upon the sheet and clamps it to the fixed gripper jaw to move it laterally toward the side gage. As the movable jaw drops, the lateral crimping falls into the position shown in dotted lines in Fig. 14, in which its lower flange 54 depresses a portion of the sheet below its plane of movement and as the lateral edge continues its movement the retarding tendency thereof gradually increases until it is brought to a full stop against the side gage. At the end of its outward movement, the dog 38 is again forced into position to open the gripper when after a brief period of rest during which the sheet is drawn from the feeder, the same operation is repeated.
- I claim:
1. In a machine of the character described, sheet-feeding means, a side gage, means for moving said sheet toward said side gage, and means for crimping the edge of said sheet to stiffen it against its impact against said side gage, said crimping means being disposed at a fixed distance from said side gage and under the control of said means for moving the sheet toward said side gage.
  2. In a machine of the character described, sheet-feeding means, a sheet-gage, a gripper reciprocable relatively to said sheet-gage, said gripper comprising fixed and movable jaws, and a dog movably mounted on said movable gripper jaw and adapted to be actuated by the reciprocatory movement of said gripper for operating said movable jaw, said movable jaw being held by said dog throughout the movement of said gripper in one direction.
  3. In a machine of the character described, a guide, a gripper reciprocable in said guide, said gripper including a movable jaw, a cam extending adjacent the line of travel of said gripper, and a dog movable on said movable gripper jaw and adapted to be engaged by said cam for holding said movable jaw in open position during the movement of said gripper in one direction and held in

position permitting said movable jaw to remain closed during the movement of said gripper in the opposite direction.

4. In a machine of the character described, sheet-feeding means, a sheet-gage, a gripper reciprocable with respect to said gage, said gripper having a rigid jaw and a jaw pivotally mounted on said rigid jaw, a cam bar, and means carried by said pivotally mounted jaw for engaging said cam bar and holding said pivotally mounted jaw in open position throughout the movement of said gripper in one direction and permitting said jaw to close during the movement in the other direction.

5. In a machine of the character described, sheet-feeding means, a sheet-gage, a gripper reciprocable with respect to said gage, said gripper having a rigid jaw and a jaw pivotally mounted on said rigid jaw, a cam bar, and means carried by said pivotally mounted jaw for engaging said cam bar and holding said pivotally mounted jaw in open position during the movement of said gripper in one direction and permitting said jaw to close during the movement in the other direction, said cam bar engaging means comprising a dog pivotally mounted on the pivotally mounted gripper jaw and movable into rigid abutment against said jaw for displacing the same, and a fixed abutment against which said dog is forced by the reciprocation of said gripper to move said dog into rigid abutment against said pivotally mounted jaw, said dog being retained in rigid abutment against said jaw by its positive engagement with said cam bar, said dog being displaced by said cam bar to release said pivotally mounted jaw by a movement of the gripper in reversed direction.

6. In a machine of the character described, sheet-feeding means, a sheet-gage, a gripper reciprocable with respect to said gage, said gripper having a rigid jaw and a jaw pivotally mounted on said rigid jaw, a cam bar, and a cam engaging dog pivotally mounted on the pivotally mounted gripper jaw and movable into rigid abutment against said jaw for displacing the same, and a fixed abutment against which said dog is forced by the reciprocation of said gripper to move said dog into cam engaging relation which retains said movable jaw in open position.

7. In a machine of the character described, sheet-feeding means, a sheet-gage, a gripper reciprocable with respect to said gage, said gripper having a rigid jaw and a jaw pivotally mounted on said rigid jaw, a cam bar, a trip lever pivoted on said pivotally mounted jaw to swing to and fro between active and inactive positions, said trip lever comprising a cam arm for engaging said cam bar and a lever arm adapted to positively engage a contiguous portion of said pivoted jaw when said trip lever is in active position, and means becoming operative at one end of the reciprocatory movement of said gripper for moving said trip lever into active position.

8. In a machine of the character described, sheet-feeding means, a sheet-gage, a gripper reciprocable with respect to said gage, said gripper having a rigid jaw and a jaw pivotally mounted on said rigid jaw, a cam bar,

and means carried by said pivotally mounted jaw for engaging said cam bar and holding said pivotally mounted jaw in open position during the movement of said gripper in one direction and permitting said jaw to close during the movement in the other direction, said cam bar engaging means comprising a dog pivotally mounted on the pivotally mounted gripper jaw and movable into rigid abutment against said jaw for displacing the same, and a fixed abutment against which said dog is forced by the reciprocation of said gripper to move said dog into rigid abutment against said pivotally mounted jaw, said dog being retained in rigid abutment against said jaw by its positive engagement with said cam bar, said dog being displaced by said cam bar to release said pivotally mounted jaw by a movement of the gripper in reversed direction.

9. In a machine of the character described, sheet-feeding means, a sheet-gage, a reciprocable gripper for moving a sheet against said sheet-gage, said gripper comprising relatively movable jaws, and means relatively to which said gripper reciprocates and controlled by the relative movement of said jaws for crimping that edge of the sheet which is presented to said sheet-gage.

10. In a machine of the character described, sheet-feeding means, a sheet-gage, a slide reciprocable with respect to said sheet-gage, said slide being provided with a rigid gripper jaw, a second gripper jaw pivotally connected to the first mentioned gripper jaw, means under the control of the reciprocatory movement of said slide for opening and closing said gripper jaws, and a sheet-crimping instrumentality oscillatable on a fixed axis and operated by said movable jaw.

11. In a machine of the character described, sheet-feeding means, a sheet-gage, a stationary shaft, a cam journaled on said shaft, a bracket secured to said shaft, a crimping member carried by said bracket, a rock shaft operated by said cam, and a crimping member mounted on said rock shaft to co-operate with the crimping member carried by said bracket.

12. In a machine of the character described, the combination with a sheet gage, of a gripper for moving a sheet up to said gage, said gripper having relatively movable jaws, and a sheet crimping instrumentality relatively to which said gripper moves a sheet, said sheet crimping instrumentality being movable into and out of crimping engagement with said sheet during its movement toward said sheet gage.

13. In a machine of the character described, a sheet gage, a gripper reciprocable with respect to said sheet gage, means for opening and closing said gripper, and sheet crimping means including an instrumentality oscillatable about an axis extending

lengthwise of the reciprocatory movement of said gripper and adapted to be oscillated by the opening and closing movements of said gripper.

5 14. In a machine of the character described, a sheet gage, a sheet crimper normally disposed in the plane of movement of a sheet, sheet gripping means for moving said sheet toward said gage and past said 10 crimper, and means operated at the end of the gripper movement for opening said gripper and moving said crimper away from the plane of movement of said sheet.

15 15. In a machine of the character described, a sheet gage, a gripper reciprocable relatively to said sheet gage, and sheet crimping means operated by and relatively to which said gripper reciprocates.

20 16. In a machine of the character described, a sheet gage, means for feeding a sheet, means for crimping a sheet as it is presented to said gage, and a sheet gripper reciprocable relatively to said gage and sheet crimping means for moving said sheet 25 against said gage, said gripper being adapted to operate said sheet crimping means by its movement relative thereto.

30 17. In a machine of the character described, a sheet gage, a reciprocable gripper for moving a sheet up to said sheet gage, said gripper having relatively movable jaws, a trip lever pivotally mounted on one of said jaws, said trip lever comprising a cam arm and a lever arm adapted to be brought into 35 positive abutment with a contiguous portion of said gripper when said trip lever is in active position, and a cam suitably disposed to be engaged by said cam arm in active position for holding the jaws of said 40 gripper open.

45 18. In a machine of the character described, a sheet gage, a reciprocable gripper for moving a sheet up to said gage, a trip lever pivotally mounted on said gripper to swing to and fro between operative and inoperative positions, and means operating throughout the movement of said gripper in one direction for holding said trip lever in operative position, said holding means 50 being adapted to permit said trip lever to assume its inoperative position throughout the movement of said gripper in the opposite direction, said trip lever in operative position being adapted to render said 55 gripper inoperative.

60 19. In a machine of the character described a sheet gage, a gripper movable toward and away from said sheet gage, said gripper being provided with a movable jaw, a cam arm pivotally mounted on said movable jaw, a cam bar extending parallel to the path of said gripper and with which said cam arm coöperates, said movable jaw in closed position being adapted to retain 65 the pivot of said cam arm nearer to the

cam bar than the length of said cam arm and means for holding said cam arm normal to said cam bar during the movement of said gripper away from said sheet gage for holding said movable jaw open.

70 20. In a machine of the character described, a sheet gage, a gripper movable toward and away from said sheet gage, said gripper being provided with a movable jaw, a cam bar arranged parallel to the path of said gripper, and a cam arm pivoted on said movable jaw, said cam arm being movable into an active position in which it is held during said gripper's movement away from the sheet gage for holding said movable jaw open, and adapted to assume an inactive position in which it is retained by the movable jaw in closed position during the movement of said gripper toward said sheet gage.

75 21. In a sheet feeding machine a sheet crimping instrumentality oscillatable about an axis, a sheet gage normal to said axis, and a sheet gripper movable toward and away from said sheet gage for moving a sheet across said sheet crimping instrumentality to said sheet gage, said sheet gripper operably engaging said sheet crimping instrumentality for oscillating the latter on its axis.

80 22. In a sheet feeding machine a sheet crimping instrumentality oscillatable about an axis, a sheet gage normal to said axis, and a sheet gripper movable toward and away from said sheet gage for moving a sheet across said sheet crimping instrumentality to said sheet gage, said sheet gripper comprising relatively movable jaws of which one operably engages said sheet crimping instrumentality for imparting the crimping movements thereto.

85 23. In a sheet feeding machine a sheet crimping instrumentality oscillatable about an axis, a sheet gage normal to said axis, and a sheet gripper movable toward and away from said sheet gage for moving a sheet across said sheet crimping instrumentality to said sheet gage, said sheet gripper comprising a rigid jaw, a movable jaw, and means operated by the movement of said gripper for operating said movable jaw, said 90 movable jaw having operating engagement with said sheet crimping instrumentality.

100 24. In a sheet feeding machine, a sheet crimping instrumentality oscillatable about an axis and comprising a lower sheet crimping flange, a sheet gage, a gripper jaw reciprocable with respect to said crimping instrumentality and sheet gage, a gripper jaw movably connected to the first mentioned gripper jaw and operably engaging the 105 upper flange of said sheet crimping instrumentality.

110 25. In a sheet feeding machine a sheet crimping instrumentality oscillatable about an axis and comprising a lower sheet crimp-

ing flange, a sheet gage, a gripper jaw reciprocable with respect to said crimping instrumentality and sheet gage, a gripper jaw movably connected to the first mentioned 5 gripper jaw and operatably engaging the upper flange of said sheet crimping instrumentality, a dog or lever for operating said movable gripper jaw, and means for operating said dog or lever to throw said movable gripper jaw into open position at one 10 end of the gripper's movement.

26. In a sheet feeding machine, a sheet crimping instrumentality oscillatable about an axis and comprising a lower sheet crimping 15 flange, a sheet gage, a gripper jaw reciprocable with respect to said crimping instrumentality and sheet gage, a gripper jaw movably connected to the first mentioned gripper jaw and operatably engaging the 20 upper flange of said sheet crimping instrumentality, said gripper being provided with a guide or track for holding said dog or lever in operative position during the movement of said gripper away from said sheet 25 gage.

27. In a sheet feeding machine, a sheet crimping instrumentality movable into and out of sheet crimping position, a sheet gage, a reciprocable sheet gripper for moving a 30 sheet across said sheet crimping instrumentality to said sheet gage, said gripper being provided with a rack, an oscillatable shaft, a gear mounted on said shaft and meshing with said rack, a guide or track, said sheet

gripper comprising relatively movable jaws, 35 and a lever or dog mounted on one of said jaws and slidably engaging said guide or track for holding said jaws open during the movement of said sheet gripper away from said sheet gage. 40

28. In a sheet feeding machine, a sheet crimping instrumentality movable into and out of sheet crimping position, a sheet gage, a reciprocable sheet gripper for moving a sheet across said sheet crimping instrumentality to said sheet gage, said gripper being provided with a rack, an oscillatable shaft, a gear mounted on said shaft and meshing with said rack, a guide or track, said sheet gripper comprising relatively movable jaws, 45 and a lever or dog mounted on one of said jaws and slidably engaging said guide or track for holding said jaws open during the movement of said sheet gripper away from said sheet gage, said gripper being provided 50 with means for operating said dog or lever to open said jaws adjacent the end of the gripper's movement toward said sheet gage. 55

29. In a sheet feeding machine, a sheet crimping instrumentality, a sheet gage distant therefrom, a sheet gripper for moving a sheet across said sheet crimping instrumentality to said gage and means operated by the movement of said sheet grippers for moving said sheet crimping instrumentality 60 into and out of operating position with respect to the sheet which is being gaged. 65
